DESIGN FOR A HANDBAG

Leo Freidman, New York, N. Y., assignor to Gold Seal Importers, Inc., New York, N. Y., a corporation of New York

Application June 21, 1940, Serial No. 93,164

Term of patent 3½ years

To all whom it may concern:

Be it known that I, Leo Freidman, a citizen of the United States and residing at New York, in the county of New York and State of New York, have invented a new, original, and ornamental Design for Handbags, of which the following is a specification, reference being had to the accompanying drawing, forming part thereof, and in which:

Fig. 1 is a front elevational view of a handbag showing my new design;

Fig. 2 is a top plan view thereof, and

Fig. 3 is a rear elevational view thereof.

The salient feature of the invention resides in the thin, exposed frame portion as best shown in Fig. 1, near the mouth of the bag and substantially encompassed by the bag portion below, above as well as at the ends of the frame, and in which said frame is completely concealed from the rear side of the bag.

I claim:

The ornamental design for a handbag, substantially as shown and described.

LEO FREIDMAN.
